(57) **CLAIM**

The ornamental design for a magnet and radio frequency detector, as shown and described.

DESCRIPTION

FIG. 1 is a front perspective view of a magnet and radio frequency detector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlargement of FIG. 1.

The dash-dash broken lines in the drawings illustrate portions of the magnet and radio frequency detector which form no part of the claimed design. The dot-dash broken lines in FIG. 1 and FIG. 9 are used to delineate enlarged views.
